UNITED STATES PATENT OFFICE.

WILLIAM CHARLES POWELL, OF ST. JOSEPH, MISSOURI.

GARMENT.

1,151,610.

Specification of Letters Patent. Patented Aug. 31, 1915.

Application filed March 8, 1915. Serial No. 12,880.

To all whom it may concern:

Be it known that I, WILLIAM C. POWELL, residing at St. Joseph, in the county of Buchanan and State of Missouri, have invented certain new and useful Improvements in Garments, of which the following is a specification.

My invention has for its object to provide a two-piece garment consisting of a coat part and a trouser part so constructed with relation one to the other that the coat part or the trousers part may be separately worn; or they may be worn together in such manner as to give the appearance of an ordinary suit; or they may be worn with the coat tucked inside at the waist to give a blouse effect; or they may be worn with either the front or back of the coat part tucked into the pants part while either the back or the front of the coat part is worn on the inside, the garment being self-supporting, *i. e.*, not requiring the use of suspenders.

Again it is an object of the invention to provide a garment of the foregoing character which will not bind in the back and will permit easy bending over without danger of tearing the parts.

The invention also resides in those novel details of construction and combination of parts, all of which will be first fully described, then be specifically pointed out in the appended claims, and illustrated in the accompanying drawings, in which:

Figure 1 is a view illustrating the invention in use, the garment being worn with the coat part out giving the appearance of an ordinary suit. Fig. 2 is a side elevation showing the belt strap secured at the front and passed through the belt loops of the coat. Fig. 3 is a view similar to Fig. 1 showing the garment worn with the coat tucked in, both front and back to give a "blouse" effect. Fig. 4 is a side elevation showing the ease with which the rear portion of the trousers part can be let down. Fig. 5 is a detail perspective view looking into the trousers part from the back toward the front and showing the button-hole strips sewn into the front of the trousers part at the waist-line. Fig. 6 is a rear elevation showing the unbroken or unopened back of the coat part.

In the drawings, in which like numerals and letters of reference indicate like parts in all of the figures, 1 represents the trousers part which is provided with the usual front

opening or fly 2, and side openings or flies 5, the openings 2 and 5 extending from the waist-line downwardly to about a position in horizontal alinement with the crotch. 60 The back of the trousers part is provided with belt loops 3 and 4 through which the belt 24 is adapted to be passed. The flies 2 and 5 have button and button-hole connections 6—7 by means of which they may be 65 closed together.

8 designates the hip pockets of the trousers part and 9 designates the front pockets which open at the sides in the usual manner.

10 designates belt loops on the front of the 70 trousers part through which the belt strap 24 is adapted to be passed when the trousers part is worn separately or when worn with the coat part tucked in at the front.

11 designates button-hole strips which 75 are sewn into the front of the trousers part at the waist-line and have button-holes 12 to receive the buttons 23 on the front of the coat part.

The coat part is composed of the back 80 section 19 and the two front sections 13, the latter being sewed to the back section 19 along the sides from the waist-line upwardly, but disconnected therefrom to provide side slits 20 from the waist-line downwardly. The front sections 13 of the coat part have button and button-hole connections 14—15 from the waist-line upwardly and are provided with suitable pockets 16, as may be desired. The coat part of the garment 85 extends downwardly from the waist-line to form a back skirt portion 21 and front skirt portions 17, the purpose of which will be apparent later. The front sections 13 of the coat part are provided with belt 90 loops 18, at the waist-line through which the belt 24 is adapted to be passed when the garment is worn as shown in Figs. 1, 2 and 3.

23 designates buttons secured in a horizontal row to the front sections 13 of the 100 coat part, at the waist-line, to button into the button-holes 12 of the pants part when the front skirt parts 17 are tucked into the trousers part, as best shown in Figs. 8 and 9. The coat part, it should be understood, may 105 be provided with the usual sleeves 22 and collar 26, when desired and the belt 24 is adapted to be buckled as at 25 to secure the ends of the same together, in the usual manner.

110 From the foregoing it will be seen that I have provided a two-piece garment, either

piece of which may be separately worn, or when the two parts are worn together, the coat part may have the skirt extensions 21—17 tucked in at the waist-line to give a "blouse" effect, as shown in Fig. 3, or they 5 may be worn outside, as shown in Figs. 1 and 2 to give a coat effect. By providing the slits 20, the belt 24 can be passed through the back loops 3 and 4 of the trousers part 10 and the front loops 18 of the coat part when the garment is worn as shown in Figs. 1 and 2, or the belt can be passed entirely through the trousers loops 3, 4 and 10 when the garment is worn as shown in Fig. 3.

15 The belt can be passed through the trousers loops 3, 4 and 10 when the front skirt sections 17 of the coat part are tucked in and the rear skirt part 21 left out, as it will be obvious that either the front or the 20 back skirt sections may be separately worn tucked in, if desired. It will also be observed that there is provided no fastenings between the back of the coat part and the back of the pants part so as to leave the 25 garment flexible at the back and allow bending over without danger of tearing the garment or putting undue strains on the back of the wearer. When the front of the coat part is tucked in at the waist-line and the 30 trousers part buttoned thereto, the garment gives the appearance of a union suit and may be worn as a union suit.

The construction is obviously adapted for 35 overalls or jumpers and may be adapted to under-garments and others as well, and I therefore do not wish to limit myself to the use of the invention on jumpers or overalls.

From the foregoing description taken in connection with the accompanying drawings, it is thought the complete construction 40 and advantages of my invention will be readily understood by those skilled in the art.

What I claim is:

45 1. In a garment, a coat part having side slits extending from the waist-line down to the lower edge, and a transverse row of buttons on the front of the coat part at the waist-line.

50 2. In a garment, a coat part having side slits extending from the waist-line down to the lower edge, a transverse row of buttons on the front of the coat part at the waist-line and belt loops on the front of the coat 55 part at the waist-line.

56 3. In a garment, a coat part including an unbroken back section and two front sections permanently secured to the back section at the sides from the waist-line upwardly and separated from the back section at the sides from the waist-line downwardly, and fastening means for securing the front sections together at the front from the waist-line upwardly.

55 4. In a garment, a coat part including an

unbroken back section and two front sections permanently secured to the back section at the sides from the waist-line upwardly and separated from the back section at the sides from the waist-line downwardly, 70 fastening means for securing the front sections together at the front from the waist-line upwardly and a horizontal row of buttons on the front sections at the waist-line.

5. In a garment, a coat part including an 75 unbroken back section and two front sections permanently secured to the back section at the sides from the waist-line upwardly and separated from the back section at the sides from the waist-line downwardly, 80 fastening means for securing the front sections together at the front from the waist-line upwardly, a horizontal row of buttons on the front sections at the waist-line, and belt loops on the front sections at the waist-line.

6. In a garment, a trousers part having a front opening and side openings extending downwardly from the waist-line, fastening means for holding the garment to close 85 the respective openings, means at the waist-line for holding the garment to the body of the wearer, and button-hole strips secured within the front of the garment at the waist-line.

7. In a garment, a coat part having side slits extending from the waist-line downwardly to the bottom to separate the coat part at the sides from the waist-line downwardly, said coat part having a horizontal 100 row of buttons at the waist-line at the front and having belt strap loops on the front, combined with a trousers part, said trousers part having side openings extending from the waist-line downwardly to about the hips, 105 means for securing said trousers part to hold said side openings closed, and a button strip secured within the trousers part at the waist-line in front to coöperate with the coat part buttons when the front of the coat 110 part is tucked in, said coat part adapted to be wholly tucked into the trousers part or to have either the front or the back of the coat part tucked into the trousers part or to have 115 both the front and the back of the coat part overlap the pants part, as desired.

8. In a garment, a coat part consisting of a continuous back section and two front sections sewn to the back section along the sides from the waist-line upwardly but disconnected from the back section from the waist-line downwardly, said front parts having button and button-hole connections from the waist-line upwardly, combined with a trousers section having side and front flies, said 120 coat part adapted to be wholly tucked into the trousers, or wholly worn outside of the trousers or worn with either the front or the back of the coat part tucked into the trousers, a button-hole strip secured at the front 125 130

within the trousers part at the waist-line and buttons on the front of the coat part to coöperate with said button-hole strips when the front of the coat part is tucked into the trousers part, said trousers part having belt loops on the front and back at the waist-line, a belt passed through said belt loops, said coat part having belt loops at the front, said belt adapted to pass through the back belt

loops of the trousers sections, and the coat 10 belt loops when the front of the coat part is worn outside of the trousers part, all being arranged substantially as shown and for the purposes described.

WILLIAM CHARLES POWELL.
